his Attorney.

UNITED STATES PATENT OFFICE.

WILLIAM B. ELLIOTT, OF CORNING, NEW YORK.

ACTUATING-PAWL FOR LAWN-MOWERS.

SPECIFICATION forming part of Letters Patent No. 268,471, dated December 5, 1882.

Application filed February 7, 1882. (No model.)

To all whom it may concern:

Be it known that I, WILLIAM B. ELLIOTT, a citizen of the United States, residing at Corning, in the county of Steuben and State of New York, have invented certain new and useful Improvements in Lawn-Mowers, of which the following is a specification, reference being had therein to the accompanying drawings.

My invention relates to actuating-paws for lawn-mowers; and it consists in the construction and arrangement of the several parts, as will be hereinafter fully set forth, and pointed out in the claim.

In the drawings, Figure 1 is a top plan view; Fig. 2, a vertical section, showing the actuating-pawl in position; and Figs. 3 and 4 are details of the same.

A A are circular disks, from the center of which project outwardly the axles *a a*, as shown. Projecting from these disks are braces *a' a'*, across the forward ends of which is secured the sickle-plate *a²*. The ends of this plate are bent and slotted, and have journaled to them the supporting-wheels *a³*.

B is the actuating-shaft. It is placed between the forward portions of the disks A A, and projects a short distance through them. Secured around it centrally, between the disks, is a pulley, *b*, which has formed in it a diagonal groove, which engages with the inner end of the lever *b'*, which is pivoted to the brace *a'*, and by its forward end to the sickle-bar *b²*, as shown. The ends of the shaft which project through the disks have horizontal slots cut in them, as shown. Within these slots are arranged T-shaped pawls *b³*. These pawls are pivoted in the outer portion of the slot, as shown, and are adapted to vibrate upon their axes or pivot-pins in the operation of the device.

C is a pinion, which revolves on the projecting ends of the shaft B. Around the bore of the pinion are formed ratchet-teeth *c*, which engage with the pawls *b³* in the operation of the machine.

D are the actuating-wheels, revolving on the

axles *a a*, as shown. The faces of their peripheries are corrugated, and around the inner sides of them are formed cogs *d*, which mesh with the teeth of the pinions C, as shown.

In the operation of the machine it will be seen that the pawls *b³* act by reason of their gravity. In the forward movement of the machine, when the shaft B has assumed a position which will bring the slot vertical, the pawls *b³* will drop by their own gravity and engage with the square shoulders of the ratchets *c*, which will cause the shaft to revolve and thence transmit its motion to the lever and sickle-bar. In the backward movement of the machine the pawls will slide up the beveled portion of the ratchets, and no motion will be imparted to the shaft. As the slot runs entirely through the shaft, and as the pawl is provided with engaging ends upon both its sides, as shown, it will be seen that the shaft will engage with as small an amount of lost motion as if two pawls upon each shaft were used.

The advantages secured by pivoting the pawls *b³* instead of arranging them to act by springs or automatically, as shown in the patents to Passmore, October 26, 1880, and January 28, 1879, are that a steadier and more certain action is secured, and that the construction of the device is more economical.

What I claim is—

In a lawn-mower, the actuating device consisting of the shaft B, having its ends slotted parallel with its axis, and having pivoted in the outer ends of said slots the T-shaped pawls *b³*, the free ends of which project out of the slot and are adapted to engage with the ratchets *c* of the pinions C, substantially as shown and described.

In testimony whereof I hereby affix my signature in presence of two witnesses.

WILLIAM B. ELLIOTT.
